UNITED STATES PATENT OFFICE

ALBERT HAPPEL, OF TOLEDO, OHIO, ASSIGNOR TO ULINE ICE SCORING MACHINE COMPANY, OF TOLEDO, OHIO, A CORPORATION OF OHIO

ICE-CUBING MACHINE

Application filed November 7, 1927. Serial No. 231,734.

The invention relates to ice cutting machines and more particularly to an ice cubing machine.

The invention has as one of its primary objects to provide a machine of the above character distinguished by its simplicity of construction and operation, which not only enhances its value both mechanically and commercially, but provides a design of a strong and durable nature.

Heretofore in the manufacture of machines for cubing ice for table use, considerable inconvenience has been commonly experienced in the necessity of positively feeding the block of ice into engagement with the saws by hand which is not only a slow and tedious operation, but is exceedingly dangerous to the operator as well.

However, according to my invention I have provided a machine wherein the block of ice is held substantially stationary and the saws for cutting the ice are moved relative to the block of ice for cubing the same. An arrangement of this character offers the possibility of eliminating the hand operation heretofore pointed out, and makes available a commercially satisfactory machine which is completely automatic in operation and is capable of producing uniform cubes. Moreover inasmuch as the machine is completely automatic in operation and owing to the fact that the ice is held stationary during the cubing operation, greater production is realized with the minimum amount of labor.

Many of the advantages and much of the commercial value and acceptability of the invention are attributed to the novel construction of the machine, these advantages being obtained particularly because of the simplicity of the construction and the minimum number of parts employed. This enables the machine to be economically and quickly manufactured and easily assembled and renders the same strong and durable.

The invention therefore depends for some of its advantages upon the specific details of construction illustrated and about to be described.

Other advantages and novel features of construction which contribute materially to

the mechanical efficiency of the apparatus also add materially to its commercial value and acceptability and many of the foregoing advantages, objects and structural features of the invention will be made more apparent as this description proceeds, especially when considered in connection with the accompanying drawings.

Figure 1 is a side elevation of the machine embodying my invention;

Figure 2 is a front elevation of the machine showing the carriage B in a position after the traversing movement of the saws C and before the vertical movement of the saws D, the machine being shown as though tilted toward the observer, and the ice feeding parts being omitted;

Figure 3 is a view similar to Fig. 2, but omitting the ice cake abutment, showing the saw carriage returning to its initial position after the horizontal and vertical operation of the saws;

Figure 4 is a detail perspective view showing a portion of the carriage guide;

Figure 5 is a detail perspective view of the abutment plate;

Figure 6 is a fragmentary sectional view showing the function of the abutment plate during the severing operation;

Figure 7 is a sectional view taken on the plane indicated by the line 7—7 of Figure 2; and

Figure 8 is a detail perspective view illustrating the connection between the main frame and the sliding frame.

In general, the machine comprises a stationary main frame A and a sub-frame B mounted on the main frame and capable of horizontal and substantially vertical movements relative to the main frame. The sub-frame or saw carriage B is fashioned to support two sets of power driven saws C, D, and a single saw E. Each of the saws C lies in a substantially horizontal plane and is mounted upon a substantially vertically extending arbor F which operates, upon movement of the carriage in a horizontal direction, to cut the cake of ice. The saws D are disposed in vertical planes and are mounted upon the arbor G which as shown extends at 100

right angles to the arbor F and operates upon a movement of the carriage in a generally vertical plane to move the saws into engagement with the ice cake and to cut 5 the same at right angles to the cuts formed by the saws C. The saw E, on the other hand, is carried by the arbor H journaled in suitable bearings formed upon the saw carriage to the rear of the arbor G and owing 10 to the fact that saw E is arranged in a plane at right angles to the planes of the saws D and spaced outwardly therefrom, it will be immediately apparent that this saw will perform the final cut to sever the ice cubes 15 from the cake of ice, the cubes falling into the chute I where they may be disposed of in any suitable manner.

In detail, the stationary frame A comprises a base 10 and a pair of standards 11 and 20 11' extending upwardly from the base and terminating in angularly offset portions 12 apertured to receive the upper ends of the angularly disposed guide rods 13 permanently secured to the base 10 as indicated at 14. 25 Disposed upon the guide rods is a frame 15 having bearing portions 16 upon the upper and lower ends thereof slidably engaging the guide rods. The bearing portions 16 are formed with extensions 17 apertured to receive a pair of horizontally disposed bars 18. Thus it will be readily apparent that the frame 15 is capable of a substantially vertical sliding movement relative to the stationary frame A. The saw carriage B is 30 mounted upon the frame 15 and is provided with bearing portions 19 slidably engaging the horizontal bars 18. Thus inasmuch as the saw carriage is mounted upon the upwardly movable frame 15 and is slidably 35 arranged upon the horizontal bars 18 of this frame, it will be readily apparent that the carriage B is capable of horizontal and substantially vertical movements relative to the stationary frame A. The saw carriage is 40 provided with the vertically aligned bearings 45 20 (Fig. 2) within which the arbor F, carrying the horizontally disposed series of saws C, is journaled.

Extending at right angles to the arbor F 45 is the arbor G journaled in bearings 21 formed in the carriage adjacent the lower end thereof and carrying the vertically disposed series of saws D. The arbor H carrying the saw E is journaled in bearings 22 55 22 formed in the lower bar 23 of the saw carriage, which as shown in Figs. 2 and 7 is in the form of a housing. The saw E, having a diameter substantially equal to the overall dimension of the series of saws D 60 (see Figs. 3 and 5) is disposed below the series of saws and is arranged in a plane at right angles thereto, the arrangement being such that when the carriage B and frame 15 move upwardly upon the guides 13 65 as a unit the saws D will cut the ice cake

at right angles to the cut formed by the saws C, and the saw E, owing to its position to the rear of the saws D, will subsequently engage the ice cake to cut the same at right angles to the cut formed by the saws.

70

For accurately guiding the carriage through the various movements heretofore pointed out, I provide the guide member 24 having integral bracket-securing portions 25, 26 and 27. The brackets 26 and 27, depending from the lower end of the guide member 24 (Fig. 2), are secured to the spaced upstanding projection 28 (Figs. 1 and 2) formed on the base 10, while the bracket 25 is secured to a projection 29 formed on the vertical upright 11 (Fig. 1). The guide member 24 in its secured position is disposed in a plane substantially parallel with the plane of the carriage B and is spaced a substantial distance therefrom. As shown in Figs. 2 and 3, 85 the guide member 24 is preferably a trapezium in shape and is composed of a substantially horizontal bar 30, a bar 31 extending upwardly from the bar 30 at right angles thereto and a tie bar 32 connecting the upper 90 end of the bar 31 and the free end of the bar 30. The tie bar 32 has an upwardly extending portion 33 arranged parallel with the bar 31. Projecting inwardly from the saw carriage B is an ear 34 (Fig. 2) upon which an arm 95 35 is rigidly secured. As shown in Fig. 4, this arm projects laterally from the carriage and bridges the space between the latter and the guide member 24 and is provided at the outer end thereof with a roller 36 arranged 1 to engage in a cam track 36' formed in the horizontal and upright bars 30 and 31 respectively.

Referring now to the specific means for driving the arbors F, G and H together with 1 the means for moving the frame 15 and carriage B relative to the stationary frame A, a suitable prime mover is provided herein shown as an electric motor 38 (Figs. 1, 2 and 3) having a shaft 39 carrying a pair of sprocket wheels 40 and 41. The sprocket 40 is connected to the sprocket 42 upon the shaft 43 by means of chain 46 and the shaft 43 is connected through suitable reduction gearing, designated generally by the reference numeral 44, to the sprocket wheel 45. The sprocket wheel 45 is in turn connected to the idler sprockets 47 and 48 journaled upon the shafts 49 and 50 mounted upon opposite ends of the horizontal bar of the guide member 24, by means of a chain 51. As clearly shown in Figure 1, the chain 51 travels in the space provided between the guide member 24 and carriage and is rigidly secured to the arm 35 adjacent the free end thereof by means of a pin 52 (Fig. 4) extending through one of the links of the chain and journaled in the channel-shaped extension 52' of the arm 35. Thus the chain 51 is connected to the saw carriage B and inasmuch as the chain is

mounted upon the stationary guide member 24, the saw carriage B will be compelled to follow the circuitous course of the chain. It will further be noted that the saw carriage 5 will move in an accurate predetermined path during the scoring of the ice irrespective of the slack in the chain owing to the connection heretofore described between the carriage B and cam groove 36' formed in the guide member 24. In order that the slack in the chain 10 may be compensated for, I provide an adjusting bracket 53 secured to the guide member 24 by means of the bolts 54, see Fig. 2. As shown, these bolts extend through suitable 15 apertures formed in the bracket and through an elongated slot 55 formed in the vertical portion 33 of the tie bar 32. A sprocket 56 is journaled upon one end of the bracket 53 and arranged to engage the chain 51. The 20 arrangement is such that when it is desired to take up on the chain 51, the bolts 54 are loosened and the bracket together with the sprocket 56 is moved upwardly longitudinally of the slot. From Figs. 2 and 3, it will 25 be clear that chain 51 has approximately the same trapezium shape as the frame 24.

For imparting a continuous drive to the arbors F, G and H throughout the several movements thereof, I provide a spline shaft 30 57 (Fig. 3) journaled in bearings 58 formed in the frame 15 at the lower end thereof. Positioned upon the spline shaft 57 adjacent one end thereof is a sprocket 58' connected to a sprocket 59 (Figs. 1 and 2), carried by the 35 swinging shaft 60, by means of a chain 61. Secured to the shaft 60 is a second sprocket 62 (Fig. 2) arranged in alignment with the driven sprocket 41 on the motor shaft 39 and connected thereto by means of the chain 63. 40 For supporting the swinging shaft 60 and accordingly the sprockets 59 and 62 in spaced relation to the spline and motor shafts, I provide adjustable members 64 and 65. Mounted upon the ends of each of these members 45 are the forks 66, 67, 68 and 69. The fork 66, upon one end of the member 64, is journaled upon the spline shaft 57, as shown in Figure 2, while the fork 67 upon the opposite end of the member 64 together with the fork 68 50 and the upper end of the member 65 constitute bearings for the shaft 60. The fork 69 is secured upon the lower end of the member 65 and journaled upon the motor shaft 39. The members 64 and 65 are each composed 55 of two bars connected together by means of adjusting nuts 70 and 71 so that the length of the chains 61 and 63 may be readily adjusted when necessary. Thus from the foregoing, it will be readily apparent that 60 the members 64 and 65 together with the shaft 60 have a grasshopper motion which permits the spline shaft 57 to move upwardly with frame 15 and at the same time effectively drive the arbors.

65 For establishing a driving connection be-

tween the spline shaft and arbors F, G and H, I provide a gear 72 (Fig. 2) keyed to the bushing 73 slidably mounted upon the splines 74 of shaft 57 and carried by the lower end of the housing 75 formed integral with the saw carriage B. Meshing with the gear 72 is a second gear 76 (Figs. 2 and 7) keyed to the shaft 77 which is journaled in the extension 23 of the housing 75 and is provided at one end thereof with a beveled gear 78 meshing with a correspondingly beveled gear 79 keyed to the arbor H. Thus a positive drive connection between the spline shaft 57 and arbor H is effected irrespective of the movement of the spline shaft. Keyed to a stub shaft 80 (Fig. 2) journaled within the housing 75 is a gear 81 meshing with the gear 76 and with a gear 82 mounted upon one end of the arbor G for driving the same. Secured to the arbor G adjacent the gear 82 is a beveled gear 83 meshing with a beveled gear 84 keyed to the lower end of the arbor F. As shown in Figure 2 of the drawings, all of the gears and respective shafts for actuating the arbors are disposed within the housing 75 of the carriage which is closed at the outer end thereof by means of the cover plate 85. Thus, in view of the fact that the driving means for the arbors as well as the arbors themselves are carried by the saw carriage, 90 the saws will be positively rotated irrespective of the movements of the saw carriage B. 95 For supporting the block of ice in proper position with respect to the saws, I provide an abutment or support 86 (Figs. 3 and 5) rigidly secured to the saw carriage as indicated generally at 87 and accordingly movable therewith. As shown, this abutment member 86 comprises a substantially flat portion 89 and an upstanding portion 90 constituting a stop for the block of ice, limiting the inward movement of the ice. The member 86 is also provided with a second substantially flat portion 91 arranged in a plane substantially lower than the plane of the portion 89 and is connected thereto by means of the inclined portion 92 (Figs. 5 and 6). The portion 89 is provided with a series of saw slots 93 for receiving the saws D and the slots 94 for receiving the two lower saws of the series 100 C. The portion 91 is provided with an aperture 94' through which the saw arbor H may project. Secured to the abutment member 86 immediately adjacent the slots 94 is a cover plate 95 (Figs. 3 and 5) cutaway as indicated 105 at 96 for receiving the saw E, which as will be noted from Figure 5 of the drawings, lies flush with the surface of the cover plate. As shown in Fig. 6, the cover plate 95 is spaced from the abutment member 86 a distance exactly corresponding to the distance the saws C and D project through the slots, or in other words the saws C and D do not project above the surface of the cover plate. The lower end 110 of the abutment member 86 is inclined with 115

respect to the horizontal, as indicated at 97 (Fig. 5), and the space between member 86 and the cover plate 95 is closed by flush riveting a strip 98 to member 86 and cover plate, 5 forming the chute I for the ice cubes cut by the machine. With the foregoing arrangement, it will be apparent that during the cutting of the ice by saws C, the upstanding portion 90 will limit the depth of the cut. More- 10 over, by reason of the fact that the cover plate is spaced from the upstanding portion 90 a distance equal to the depth of the cuts made by the saws C and D, and inasmuch as the saw E lies substantially flush with the surface 15 of the cover plate and follows the saws D during the upward movement of the saw carriage B and cover plate to sever the cubes from the block of ice, the portion of the ice block from which the cubes have been severed 20 will be supported directly upon the cover plate 95 until the saw E has completed its cut. The cubes, as they are severed from the ice block, will slide down the inclined portion 92 under the saw E and into the chute I, and so 25 out of the machine. See Figs. 5, 6 and 3.

For supporting the ice block 99 in position to be operated on by the saws, I provide a platform 100 (Figs. 1 and 6) and an elevating platform 101 positioned adjacent to the platform 100 and having the forward end thereof normally engageable with the floor line so that the ice block may be readily positioned upon the platform 101 without lifting the same. After the block of ice is placed upon 30 the platform 101 the latter may be elevated (by operating a windlass 101' actuated by the crank 102) to substantially the same level as the platform 100, whereupon the ice is merely slid off upon this latter platform 35 against the supports 103 projecting upwardly from the sides of the platform 100. Owing to the fact that the horizontal cutting of the ice is in the direction of the supports 103 the ice will be firmly held thereagainst.

40 To eliminate positively feeding the ice into position to be engaged by the saws, the platform together with the saw carriage and frame 15 are arranged at an angle to the horizontal, as clearly shown in the drawings, so 45 that the ice by reason of its own weight will automatically move into engagement with the saws C at the completion of each cut.

While it is believed that the operation of the machine will be thoroughly understood 50 from the foregoing description, a brief outline thereof will be given. The block of ice is properly positioned upon the platform in the manner heretofore pointed out and the prime mover is started which drives the arbors F, G and H and at the same time through 55 the chain 46 imparts rotation to the sprocket 45, which in turn drives the chain 51. The latter, owing to its connection to the saw carriage B, will move the saw carriage hori- 60 zontally upon the guide bars 18 to a position

where the series of saws C engage the block of ice and form the horizontal cut, which is shown completed in Figure 2. After this cut has been completed, the saw carriage, together with the support 87, frame 15 and 70 accordingly its spline shaft 57 move upwardly as a unit to first engage the saws D with the block of ice to cut the same vertically and to subsequently engage the saw E with the ice to score the same at right angles to 75 the cut aforesaid, whereupon uniform cubes are severed from the block of ice. The cover plate 95, as heretofore pointed out, immediately follows the saws and engages the portion of the block of ice from which the cubes 80 have been cut to hold the same in position upon the platform 100 until the carriage returns for the second series of operations. After the saw carriage has completed the 85 horizontal and vertical movements set forth above, the chain carries the saw carriage diagonally across the frame 24. During the diagonal travel of the carriage, the latter will move horizontally along the guide bars 18 and splines 74, while these members at the 90 same time are being lowered upon the guides 13 toward their initial position. When the frame 15 has assumed its initial starting position the carriage will be located at the extreme left hand side of Figure 2. Figure 3 95 of the drawings clearly illustrates the position of the various parts during the return movement of the saw carriage.

Thus from the foregoing, it will be readily apparent that the machine illustrated herein 100 is completely automatic in the cubing operation and inasmuch as the block of ice is held substantially stationary during the scoring of the same, a greater production of ice cubes is realized with the minimum amount of 105 labor.

Obviously, the present invention is not restricted to the particular embodiment thereof herein shown and described. Moreover, it is not indispensable that all the features of the invention be used conjointly, since they may be employed advantageously in various combinations and sub-combinations.

What I claim as my invention is:

1. A machine for cutting blocks from a 115 cake of ice comprising, in combination, a stationary frame, a carriage supported by said stationary frame and capable of movement relative thereto, a plurality of arbors carrying cutting means journaled upon said carriage and extending at substantially right angles to each other, and means for moving said saw carriage in the direction of the axes of said arbors to successively bring said cutting means into engagement with the ice cake 120 to sever blocks therefrom.

2. In a machine for cutting ice, the combination with means for positioning a cake of ice to be cut, of a plurality of saw arbors 125 carrying saws angularly spaced with respect 130

- to each other, and means for moving said saw arbors as a unit in transverse directions to successively bring the saws into engagement with the cake of ice to cut the same in corresponding directions. 5
3. In a machine for cutting ice, the combination with means for positioning a block of ice to be cut, of a plurality of saw arbors carrying saws, said arbors having the axes thereof angularly arranged with respect to each other, means for moving said saw arbors as a unit in directions paralleling the axis of each arbor to successively engage the saws with the block of ice to cut the same in transverse directions, and means for positively driving said arbors throughout the movements thereof. 10
4. In a machine for cutting ice, the combination with a plurality of angularly disposed saw arbors and saws upon said arbors, of means for moving said saw arbors as a unit in an annular path corresponding to the angle formed by said arbors, whereby movement of the unit in one direction causes one series 20 of saws to move into engagement with a block of ice to cut the same in one direction and subsequently to move another series of saws into engagement with the block of ice to cut the same at an angle to the cut aforesaid. 25
5. In a machine for cutting ice, the combination with a carriage having a plurality of saw arbors carrying saws, of means for moving said saw carriage in one direction to bring one series of saws into engagement with a block of ice to cut the same in a corresponding direction, said means also being operable to move said carriage in another direction transverse to the direction aforesaid to bring 30 a second series of saws into engagement with the ice block to cut the same transversely to the cut aforesaid and to subsequently bring a third saw into engagement with the ice to cut the same transversely to both the cuts aforesaid and thereby sever a portion from the block of ice. 40
6. In an ice cubing machine, the combination with a carriage having a substantially vertically extending saw arbor journaled thereon carrying a series of horizontally disposed saws, of a second saw arbor journaled upon said carriage at substantially right angles to the saw arbor aforesaid and carrying a series of vertically disposed saws, a 50 third saw arbor journaled upon said carriage at substantially right angles to said second saw and carrying a saw disposed in a plane extending at substantially right angles to the plane of the saws aforesaid, said last mentioned saw being spaced laterally from the second mentioned saws, and means operable to move said carriage in one direction to bring said first mentioned saws into engagement with the ice to cut the same horizontally 60 and to subsequently move said carriage in another direction to bring said second and third mentioned saws into engagement with the ice to respectively cut the same substantially at right angles to the cut aforesaid and to each other to sever cubes from the block of ice. 70
7. In a machine for cutting ice, the combination with means for positioning a block of ice to be cut, of a carriage movable relative to said positioning means carrying a plurality of angularly disposed saw arbors, saws upon said arbors, and means for moving said saw carriage in a cycle determined by the angular relation of said saw arbors to successively bring said saws into engagement with the block of ice to cut the same in transverse directions. 75
8. In a machine for cutting ice, the combination with a stationary support for positioning a block of ice to be cut, of a carriage movable relative to said support, a plurality of groups of saws mounted upon said carriage, and means for moving said carriage in a predetermined path to successively bring the groups of saws into engagement with the ice to cut the same in transverse direction. 85
9. In a machine for cutting ice, the combination with a stationary support for positioning a block of ice to be cut, of a carriage movable relative to said support, a plurality of groups of saws angularly disposed upon said carriage, means for moving said carriage in one direction to cause one group of saws to cut the ice in a corresponding direction and to subsequently move the carriage in another direction to cause a second group of saws to cut the ice at an angle to the line of said first mentioned cut, and a third saw operable during the movement of said carriage in said last mentioned direction for severing the cut portions from the body of the block. 95
10. In a machine for cutting ice, the combination with a support for positioning a block of ice to be cut, of a carriage movable relative to said support, a group of saws upon said carriage, means for moving said carriage in one direction to cause said group of saws to cut the ice in a corresponding direction, and another saw mounted upon said carriage and operable upon movement of the same in the direction aforesaid to sever the cut portions from the block of ice. 100
11. In a machine for cutting ice, the combination with means for positioning a block of ice to be cut, of means for severing portions from the block of ice including a carriage movable relative to said positioning means, a group of saws upon said carriage, means for moving said carriage in one direction to cause said saws to cut the ice in a corresponding direction, a second saw also mounted upon said carriage and operable upon movement of the latter in the direction aforesaid to cut the block of ice transversely of the first mentioned cut and sever portions thereof. 110
12. In a machine for cutting ice, the combination with means for positioning a block of ice to be cut, of means for severing portions from the block of ice including a carriage movable relative to said positioning means, a group of saws upon said carriage, means for moving said carriage in one direction to cause said saws to cut the ice in a corresponding direction, a second saw also mounted upon said carriage and operable upon movement of the latter in the direction aforesaid to cut the block of ice transversely of the first mentioned cut and sever portions thereof. 120
13. In a machine for cutting ice, the combination with means for positioning a block of ice to be cut, of means for severing portions from the block of ice including a carriage movable relative to said positioning means, a group of saws upon said carriage, means for moving said carriage in one direction to cause said saws to cut the ice in a corresponding direction, a second saw also mounted upon said carriage and operable upon movement of the latter in the direction aforesaid to cut the block of ice transversely of the first mentioned cut and sever portions thereof. 125

tions therefrom, and means movable with said carriage and operable upon movement of the latter in the direction aforesaid to support the portion of the ice block from which the cut portions have been severed.

12. In a machine for cutting ice, the combination with means for positioning a block of ice to be cut, of means movable relative to said positioning means and operable to cut the ice in transverse directions to sever polygonal portions therefrom, and means carried by the second mentioned means operable to limit the extent of said cut within the ice and to engage the portion of the ice from which the polygonal portions have been severed for supporting the block of ice and preventing movement of the same during the cutting operation.

13. In a machine for cutting ice, the combination with means for positioning a block of ice to be cut, of means for severing portions from the block of ice including, a carriage movable relative to said positioning means, a group of saws upon said carriage, means for moving said carriage in one direction to cause said saws to cut the ice in a corresponding direction, a second saw also mounted upon said carriage and operable upon movement of the carriage in another direction to sever the cut portions from the block of ice, and a member secured to said carriage having a portion operable during the movement of said carriage in said first mentioned direction for limiting the extent of said cut, said member having another portion spaced above the portion aforesaid and arranged in the plane of said second saw for supporting the portion of the ice block from which the cut portions aforesaid have been severed.

14. In a machine for cutting ice, the combination with a stationary frame having an upwardly extending guide member, of a sub-frame slidably mounted upon said guide member having a substantially horizontally disposed guide bar, a saw carriage slidably mounted upon said bar carrying a plurality of angularly spaced groups of saws, and means positioned upon said stationary frame and connected to said saw carriage for moving the latter and the sub-frame to bring said saws into engagement with the block of ice to cut the same in directions parallel to said guide member and guide bar.

15. In a machine for cutting ice, the combination with a stationary frame, of a sub-frame slidably mounted upon said stationary frame, a saw carriage slidably mounted upon said sub-frame and carrying a plurality of angularly spaced saws, and means positioned upon said stationary frame and connected to said saw carriage for moving the latter and the sub-frame to bring said saws into engagement with a block of ice to cut the same in transverse directions, said means

being subsequently operable to move said saw carriage back to its initial position thereby completing the cycle.

16. In a machine for cutting ice, the combination with a stationary frame, of a sub-frame mounted upon said stationary frame and capable of substantially vertical sliding movement with respect thereto, of a saw carriage slidably mounted upon said sub-frame in a direction transverse to the direction aforesaid, a plurality of angularly spaced saws upon said carriage and means connected to said carriage for sliding the same upon said sub-frame to bring one group of saws into engagement with a block of ice to cut the same, said means also being operable to slide said sub-frame and carriage upon said stationary frame to cause a second group of saws to cut the ice in transverse directions to the direction of said first mentioned cut, said means being subsequently operable to move said carriage angularly to the transverse sliding movements of the sub-frame and carriage aforesaid to return the latter together with the sub-frame to their initial position.

17. In a machine for cutting ice, the combination with a stationary frame, of a carriage carried by said frame and movable with respect thereto, a plurality of groups of saws mounted upon said carriage, means for moving said carriage in a plurality of predetermined directions to successively bring the groups of saws into engagement with a block of ice to cut the same in transverse directions, and means for accurately guiding said carriage during the cutting of the block of ice, said means including a member secured to said frame and having a cam groove therein for receiving a projection upon said carriage.

18. In a machine for cutting ice, the combination with a stationary frame, of a saw carriage carried by said frame and movable with respect thereto, a plurality of angularly spaced saw arbors journaled upon said carriage, saws on said arbors, a prime mover upon said stationary frame, a connection between said prime mover and saw carriage for moving the latter in a plurality of predetermined directions to successively engage the saws upon the arbors with a block of ice to cut the same in transverse directions, and means also connected to said prime mover for positively rotating said arbors irrespective of the movements of said carriage.

19. In a machine for cutting ice, the combination with a stationary frame and a support for positioning a block of ice to be cut, of a carriage supported by said stationary frame and movable with respect thereto, a plurality of groups of saws mounted upon said carriage and means for moving said carriage in a predetermined cycle to successively bring said groups of saws into engagement with the ice to cut the same in transverse directions.

directions, said support and carriage being disposed in planes extending at angles to the direction of feed of the ice block so that the latter will automatically move into engagement with the saws at the completion of each cycle.

20. A machine for cutting blocks from a cake of ice including a frame, a carriage supported by said frame and movable with respect thereto in directions substantially at right angles to each other, and a plurality of saws arranged upon the carriage to successively engage the cake of ice during movement of the carriage in the directions afore-
10 said for severing blocks from the cake of ice.

21. In a machine for cutting ice, the combination with a carriage, of a plurality of saw arbors angularly arranged upon said carriage, saws mounted upon said arbors, and means for moving said carriage in the direction of the axis of each of said arbors to successively engage the saws with a cake of ice to cut the same.
15

22. A machine of the character described comprising, in combination, a frame, a carriage angularly movable with respect to said frame, a plurality of angularly arranged saw arbors journaled upon said carriage and carrying saws, the angle formed by said arbors corresponding to the path of travel of said carriage during the active work of the machine, whereby the saws upon movement of the carriage successively engage the cake of ice to cut the same.
25

23. An ice cubing machine comprising, in combination, a series of saws mounted on a power-driven arbor; means for feeding a cake of ice against said saws; means for arresting the cake of ice after it has been fed a predetermined distance; a carriage on which said arbor is mounted; a second series of saws at right angles to the first series and mounted on another power-driven arbor on the carriage; means for mounting the carriage so as to be movable in two paths at right angles, each path being parallel to the planes of the saws of one of said series; and power-driven means for moving the carriage.
35

24. An ice cubing machine comprising, in combination, a series of saws mounted on a power-driven arbor; means for feeding a cake of ice against said saws; means for arresting the cake of ice after it has been fed a predetermined distance; a carriage on which said arbor is mounted; a second series of saws at right angles to the first series and mounted on another power-driven arbor on the carriage; means for mounting the carriage so as to be movable in two paths at right angles, each path being parallel to the planes of the saws of one of said series; another power-driven saw on the carriage so arranged as to cut off the cubes outlined by the scorings from the two series of saws;
45

and power-driven means for moving the carriage.

25. An ice cubing machine comprising, in combination, an inclined platform for ice cakes; a saw carriage movably mounted adjacent the lower end of said platform; a series of saws on the carriage arranged parallel to the inclined platform; a second series of saws at right angles to the first series and also on the carriage; means for moving the carriage first parallel and then at right angles to the inclined platform; and means for driving both series of saws while the carriage is in motion.
75

26. An ice cubing machine comprising, in combination, an inclined platform for ice cakes; a saw carriage movably mounted adjacent the lower end of said platform; a series of saws on the carriage arranged parallel to the inclined platform; a second series of saws at right angles to the first series and also on the carriage; means for moving the carriage first parallel and then at right angles to the inclined platform; a single saw also mounted on the carriage and arranged to cut off the cubes of ice after the second series of saws have cut the transverse scores, and during the same movement of the carriage; and means for driving all of the saws while the carriage is in motion.
80

27. A machine for cutting cubes of ice from ice cakes comprising, in combination, a stationary frame; a stationary ice cake support spaced from said frame; a movable frame mounted on the stationary frame for up and down movements in a path generally perpendicular to the bottom of the ice cake support; a saw carriage movably mounted on the movable frame for transverse movements in a path substantially parallel to the bottom of the ice cake support; three saws on the saw carriage lying in three planes at right angles to each other; means for rotating the saws irrespective of movement of the carriage; and means for moving the carriage transversely across the end of the ice cake support so that one of said saws scores the ice cake, then moving the movable frame and carriage as a unit upwardly so that the second saw scores the ice cake substantially at right angles to the first score, and the third saw follows immediately after and severs the cube from the cake of ice during the same upward movement of the carriage.
100

28. A machine for cutting cubes of ice from ice cakes comprising, in combination, a stationary frame; a stationary ice cake support spaced from said frame; a movable frame mounted on the stationary frame for up and down movements in a path generally perpendicular to the bottom of the ice cake support; a saw carriage movably mounted on the movable frame for transverse movements in a path substantially parallel to the bottom of the ice cake support; three saws on the
105

saw carriage lying in three planes at right angles to each other; means rotating the saws irrespective of movement of the carriage; and means for moving the carriage transversely 5 across the end of the ice cake support so that one of said saws scores the ice cake, then moving the movable frame and carriage as a unit upwardly so that the second saw scores the ice cake substantially at right angles to the 10 first score, and the third saw follows immediately after and severs the cube from the cake of ice during the same upward movement of the carriage; said carriage-moving means comprising an endless chain carried on 15 said stationary frame and lying in a plane substantially perpendicular to the bottom of the ice cake support; means for pivotally securing the carriage to the chain; means for guiding the chain; and motor-actuated means 20 for driving the chain.

29. A machine for cutting cubes of ice from ice cakes comprising, in combination, a stationary frame; a stationary ice cake support spaced from said frame; a movable frame 25 mounted on the stationary frame for up and down movements in a path generally perpendicular to the bottom of the ice cake support; a saw carriage movably mounted on the movable frame for transverse movement in a 30 path substantially parallel to the bottom of the ice cake support; three saws on the saw carriage lying in three planes at right angles to each other; means for rotating the saws irrespective of movement of the carriage; and means 35 for moving the carriage transversely across the end of the ice cake support so that one of said saws scores the ice cake, then moving the movable frame and carriage as a unit upwardly so that the second saw scores the ice 40 cake substantially at right angles to the first score, and the third saw follows immediately after and severs the cube from the cake of ice during the same upward movement of the carriage; said carriage-moving means comprising 45 an endless chain; a cam groove provided on the stationary frame; a roller carried by the carriage and projecting into the cam groove; a pivot connecting the chain with the carriage; the chain lying in a plane substantially parallel to the carriage; and motor-actuated means 50 for driving the chain.

30. A machine for cutting cubes of ice from ice cakes comprising, in combination, a stationary frame; a stationary ice cake support spaced from said frame; a movable frame mounted on the stationary frame for up and down movements in a path generally perpendicular to the bottom of the ice cake support; a saw carriage movably mounted 55 on the movable frame for transverse movements in a path substantially parallel to the bottom of the ice cake support; three saws on the saw carriage lying in three planes at right angles to each other; means for rotating the saws irrespective of movement of the 60

carriage; and means for moving the carriage transversely across the end of the ice cake support so that one of said saws scores the ice cake, then moving the movable frame and carriage as a unit upwardly so that the second saw scores the ice cake substantially at right angles to the first score, and the third saw follows immediately after and severs the cube from the cake of ice during the same upward movement of the carriage; 70 said carriage-moving means comprising an endless chain pivotally connected to the carriage and lying in a plane substantially parallel to the carriage and being between the carriage and the stationary frame; means for guiding the chain so that it has the shape of a trapezium; the stationary frame providing a cam groove on two sides at right angles; the carriage having a roller projecting into the cam groove so that the carriage is guided during the scoring and cutting by the aforesaid saws. 75

31. In an ice cubing machine, in combination, means for feeding the ice by gravity; a power-driven rotary saw against which the ice is pressed by gravity; a second power-driven rotary saw at right angles to the first; a third power-driven saw for severing the cube scored by the first two saws; and means 80 for mounting said saws so that the three 90 saws cut the ice successively. 95

32. In an ice cubing machine, in combination, an ice cake support providing means for feeding the cake by gravity; a pair of scoring saws at right angles to each other and movably mounted so as to score one face of the ice cake when on said support; an abutment means against which the cake presses by gravity; and another scoring saw at right angles to each of the others to sever 100 the scored cube from the cake. 105

33. In an ice cubing machine, in combination, an ice cake support; two power-driven arbors at right angles to each other and each carrying a series of scoring saws, one arbor being substantially perpendicular to the bottom of the support and the other being substantially parallel to said bottom; means for mounting said arbors for rotary movement and for traversing movements in two directions across one face of an ice cake on the support; and another saw on said arbor mounting means, said other saw having a diameter substantially equal to the distance between the end saws of one of the series of saws, and lying at right angles to the planes of the saws of said series, with its plane tangential to said saws. 110 115

In testimony whereof I affix my signature.

ALBERT HAPPEL.
